Inventor:

UNITED STATES PATENT OFFICE.

RICHARD T. NEWTON, OF NEW YORK, N. Y.

AUTOMOBILE-BUMPER.

1,380,239.

Specification of Letters Patent. Patented May 31, 1921.

Application filed January 22, 1917. Serial No. 143,815.

To all whom it may concern:

Be it known that I, RICHARD T. NEWTON, a citizen of the United States of America, and residing in the city, county, and State 5 of New York, have invented a certain new and Improved Automobile-Bumper, of which the following is a specification.

My invention relates to automobile bumpers and particularly to bumpers of the flat 10 spring type, the object of my invention being to provide an improved construction in this type of bumper which possesses the advantage of adjustability to different widths of chassis, ready attachability, economy of construction, and increased efficiency and strength.

In the accompanying drawing,

Figure 1 is a plan partially in section of a bumper in which my invention is embodied in one form;

Fig. 2 is a front elevation thereof;

Fig. 3 is an enlarged side elevation indicating the manner of attachment to the side frame of the chassis;

Fig. 4 is a section on the line 4—4, Fig. 3;

Fig. 5 is a partial sectional plan of a modified construction of the springs;

Fig. 6 is a similar view of a further modification;

Fig. 7 is a side elevation of a further modification of the attaching end of the springs; and

Fig. 8 is a section on the line 8—8, Fig. 7.

Referring to the drawings, the bumper in 35 the construction illustrated in Figs. 1 to 4 comprises two pairs of flat springs 10, 11 and 12, 13, arranged on edge, one behind the other in the same substantially horizontal plane and secured at the inner ends in 40 any suitable fashion to the side bars 14 and 15 of the chassis frame. The outer ends of the springs are gripped between a pair of clamping plates 16 and 17 united by a clamping bolt 18.

In order to hold the springs securely between the clamping plates I form studs 19 on the latter which take into corresponding apertures or recesses 20 in the ends of the springs. By providing a series of apertures 50 in the outer spring ends, it is possible to vary the spacing of the springs 10—12 from the springs 11—13 to accommodate the bumper to various widths of chassis.

The springs 10 and 11 extend on a gradual broad curve 21 from the opposite ends of the mid clamp 16—17 to the side bars

14—15 of the chassis and are provided at their extremities with a straight reach adapted to lie against the vertical face of the chassis side channels 14—15. The 60 springs 12 and 13 lie outside the springs 10 and 11 and form the impact member of the bumper. They extend laterally in opposite directions from the mid clamp in a very gradual curve to points sufficiently far beyond the chassis to protect the wheels (indicated in dotted lines) and at this point 22 are sharply recurved into supporting arms 23, the extremities of which are straight and register with the like portions of springs 70 10 and 11. It is obvious from the shape of springs 10 and 11 that these afford a greater resistance to flexion than the impact springs 12—13 and they strongly reinforce the latter and take the heavier stresses incident to 75 shock. To this end they may be made of heavier stock than the impact springs, or if it is desired to more nearly equalize the strength of all the springs, the impact springs 12—13 may be made of the heavier 80 stock.

The bumper is secured to the chassis side bars in any convenient fashion. I have shown the spring ends clamped in position by means of upper and lower hooks 24 and 85 25, which span the upper and lower flanges 26—27 of the channel and engage the inner edges thereof, while clamping screws 28—29 pass through offset flanges 30—31 at their outer ends into engagement with the springs. 90 A very secure anchorage is thus attained.

It will be noted that in the construction described the bumper presents a symmetrical structure on opposite sides of the mid-clamp or connector 16—17. It embraces, in 95 other words, two attaching members of spring steel, or other resilient strip, which are of duplex character. These attaching members comprise a plurality of strips extending from the spring bends 21 and 23 100 and engaged by a supporting clamp 24, or by bolts 39, 40 (Fig. 8) passing through holes therein, and by which they are attached to the chassis. The curved yielding portion 21 of the inner strip of one attaching member merges into the connector portion thereof engaged by the mid-clamp or connector 16—17; while the other strip has a co-operating connector portion extending outwardly as the end of the impact-receiving portion of the bumper, an end loop 22 and curved yielding portion 23. The co- 110

operating connector portions of each of these resilient elements may have their ends substantially in line, and may be adjusted or otherwise connected to a front connector 5 16—17, the studs 19 of which have at least considerable vertical alining action on the coöperating connector portions of the resilient strip elements. The bolt 18 connects each of these strip elements to the front connector 16—17, while the apertures 20 in the 10 ends of the strip elements, permit these elements to be adjustably spaced apart.

In the modification Fig. 5 I have shown the inner springs 10 and 11 combined into 15 a single integral spring 32. Inasmuch as the spring 32 is integral throughout, the clamping plate 16 may be dispensed with and only the plate 17 utilized. I have here shown it tapped to receive the screw bolt 20 33 which passes through a hole in the spring 32.

In Fig. 6 I have shown both the inner spring 32 and the impact spring 34 integral throughout. The two springs are held by 25 the mid clamp to prevent rattling and to so combine their efforts as to distribute the strain on shock to the bumper.

In Figs. 7 and 8 a modified form of attachment to the chassis is indicated. The 30 inner ends of the springs 35 and 36 are turned down to form vertical arms 37 and 38 through which pass the hook bolts 39 and 40. Either one or both of the vertical arms 37 or 38 may be offset at its lower end to 35 form a flange 41 lying beneath the lower flange of the chassis side channel and pierced to receive heavy set screws 42 which lie on opposite sides of the axis of the bolts 39—40 and bear against the lower channel flange 40 27. These screws 42 not only draw the bumper arms down rigidly against the upper clamping bolt 39 but also afford means for the horizontal alinement of the bumper since the hole through which the lower bolt 45 40 passes is given the form of a slot so that the bumper may be rocked on the upper bolt 39 by adjustment of the set screws 42 to different positions. If the bumper is attached to the downwardly curved portion 50 of the chassis side bar, this feature of construction becomes a necessity in order to secure the proper alinement of the bumper.

I wish to lay special stress on the fact 55 that the impact and reinforcing spring bars form independent integers, except so far as they co-act in meeting strains imposed upon the bumper. This co-action is the result of their juxtaposition at the mid portion of the impact bar and their independent attachment to the chassis frame without intermediate union between the spring elements. The mid clamp of the bumper serves to unite 60 the bars in the construction shown in Figs. 1 to 4, but it is merely a preferred non-65 essential, (to prevent rattling), when one

or both of the bars are integral from end to end of the bumper, as shown in Figs. 5 and 6. This co-acting independence of the spring bars results in a much stronger construction than has hitherto been attained in 70 this general type of bumper, since each spring bar is carried back in its full strength to its point of support. Each bar thus takes its own entire weight and the strains placed thereon. For an equal weight of spring, 75 twice the strength is secured over a construction in which the entire weight of the bumper is carried by the extended attaching arm of the impact spring, as in certain 80 previous constructions. Another great advantage of the present construction is found in the fact that the weight of the bumper is hung close to its point of support, whereas in other constructions of the same general type, the weight and strength are at 85 the outer or forward portion of the bumper, with consequent relatively heavy strains on the inner point of support, particularly as this latter construction causes excessive vibration during road travel, and this tends 90 to break the bumper at its point of support on the chassis, due to crystallization in the bars, and also to loosen the supporting brackets, by which the bumper is secured to the chassis. Engaging the impact spring 95 at its weakest point, viz., its mid area, the reinforcing spring of this present construction supports the impact bar with a greater strength than that possessed by the impact bar itself, owing to the different curvatures of 100 the two bars and their independent extension through to the chassis. Actual tests have proven the present lighter construction twice as strong as the best bumpers of like general type, even when the latter are 105 of heavier construction.

The present construction is equally effective against strains on the bumper due, not to impact, but to forward angular strains, such as are caused when one end of the 110 bumper is hooked by a passing car or by a pole or tree when the car is backed. While in most bumpers a strain of this sort causes breakage, the present bumper is sufficiently flexible and, at the same time, strong enough 115 to permit movement of the car and still not injure the bumper.

Various modifications of general contour of the springs, and of the construction of the mid clamp, as well as of the means for securing the bumper to the chassis will readily occur to those skilled in the art without departing from what I claim as my invention.

I claim:—

1. An automobile bumper comprising a flat spring having an impact portion extending in substantially horizontal position transversely of the car and beyond the side of the chassis, when mounted, and a portion 130

recurved from the outer end of said impact portion toward the chassis, in combination with a reinforcing flat spring lying in substantially the same horizontal plane but of 5 less transverse extent and having its outer end extending on a more gradual and a stronger curve toward the chassis, together with means uniting said springs toward the mid portion of the bumper to secure their 10 co-action, and means engaging the chassis ends of said impact and reinforcing springs to secure the same to the chassis.

2. An automobile bumper comprising a flat spring having an impact portion extending in substantially horizontal position transversely of the car, when mounted, to a point in front of a side wheel and a portion recurved from the outer end of said impact portion toward the chassis of the car, 15 in combination with a reinforcing flat spring lying in substantially the same horizontal plane but of a transverse width limited substantially by the width of the chassis and extending toward the latter on a more gradual 20 and stronger curve, together with means for uniting said springs toward the mid-portion of the bumper to secure their co-action, and means engaging the chassis ends of said impact and reinforcing springs to secure the 25 same to the chassis.

3. An automobile bumper comprising a flat spring having an impact portion extending in substantially horizontal position transversely of the car when mounted and a 30 portion recurved toward the chassis from the end of said impact portion, in combination with a reinforcing flat spring of greater resistance to flexion lying in substantially the same horizontal plane and having its outer end curved toward the chassis, together 35 with means for uniting said springs toward the mid-portion of the bumper to secure their co-action, and means engaging the chassis ends of said impact and reinforcing elements to secure the same to the chassis.

4. An automobile fender comprising a front part of flat metal extending across the vehicle in advance thereof, supports for the ends of said part comprising strips of resilient flat metal extending from the ends of the front part to the adjacent ends of the vehicle frame, said strips being bowed with their convex faces toward the front, and a middle support for said front part extending from the middle of the front part to the said ends of the vehicle frame, said middle support being formed of resilient flat metal curved to bow-form substantially throughout the length of the support with the convex side of the bow faced toward the front end away from the center of the vehicle whereby the support forms an arch with its crown attached to the front part of the fender.

5. An automobile bumper comprising an

impact structure extending across the vehicle front beyond the opposite chassis side bars, and at each end of said structure a spring supporting arm extending on a curve toward the chassis and a reinforcing spring 70 arm supporting the mid-area of the impact member and extending from the latter toward the chassis, the attaching ends of said impact and reinforcing arms extending substantially parallel to each other and forming 75 together a pair of attaching legs through which the strains on the bumper are transmitted to the chassis.

6. In a construction such as specified in claim 5, means for securing together said impact member and reinforcing member toward the mid-area of the bumper.

7. An automobile bumper comprising an impact member of spring strap material, having supporting arms extending on a 85 curve from the ends of the impact member to the chassis, and a reinforcing spring arch lying between the impact member and the chassis and serving to support the mid-area of the impact member, the attaching legs of 90 the spring arch being rigidly supported with respect to the chassis to transmit directly thereto the strains imposed on said spring arch.

8. An automobile bumper comprising an impact member of spring strap material, having supporting arms extending on a curve from the ends of the impact member to the chassis, and a reinforcing spring arch lying between the impact member and the chassis 100 and serving to support the mid-area of the impact member, the attaching ends of said supporting arms and spring arch lying substantially in parallel, together with means for securing the attaching ends of said supporting arms at opposite sides of the bumper respectively to a common support at opposite sides of the chassis.

9. An automobile bumper comprising an impact member of spring strap material, 110 having supporting arms extending on a curve from the ends of the impact member to the chassis, and a reinforcing spring arch lying between the impact member and the chassis and serving to support the mid-area 115 of the impact member, the attaching ends of said impact member and supporting arch lying substantially parallel to each other, and to the opposite chassis side bars, together with means common to the attaching 120 ends for opposite sides of the bumper for securing the same respectively to the opposite chassis side bars.

10. An automobile bumper having an impact member extending completely across 125 the vehicle end, a pair of end supporting arms of spring metal, a pair of spring metal arms for supporting the mid-area of the bumper, the attaching ends of said end and mid-area supporting spring arms for oppo- 130

site sides of the bumper respectively approaching each other, and being carried toward the chassis substantially parallel, together with means for securing the supporting arms at each side of the bumper respectively, to a common support.

11. An automobile bumper having an impact member extending completely across the vehicle end, a pair of end supporting arms of spring metal, a pair of spring metal arms for supporting the mid-area of the bumper, the attaching ends of said arms approaching each other and being carried toward the chassis substantially parallel at opposite sides of the bumper respectively, together with means for securing the supporting arms at each side of the bumper respectively to a common support.

12. An automobile bumper having an impact member extending completely across the end of the vehicle chassis, spring supporting arms for the opposite ends thereof, and an independent spring support for the mid-area of the bumper comprising arms extending from the mid-area of the bumper in opposite directions toward the bumper end support arms, and means for engaging the end and mid-supporting arms at each end of the bumper respectively to a common support.

13. An automobile bumper comprising an impact member extending completely across the end of the vehicle chassis, spring end supports therefor, reinforcing spring means arranged between the mid-area of the impact member and the chassis, the chassis ends of the spring end and mid-reinforcing arms being carried inwardly and independently toward the chassis, and means engaging the said supporting arms at opposite ends of the bumper respectively, to secure the same to a common support at each side of the chassis.

14. An automobile bumper comprising a transverse impact member of spring flat metal recurved at its opposite ends to form spring supporting arms, and means for attaching said arms to a rigid support, in combination with auxiliary spring flat metal supports extending from said point of attachment toward the mid-area of the impact member of the bumper to reinforce the latter.

15. In an automobile bumper, a transverse impact member, spring supporting arms extending from opposite ends thereof, and a yielding arch-like support for the mid-area of the bumper, the attaching legs of said arch-like support being carried respectively to a point of support rigid with the chassis and serving to transmit thereto directly the strains imposed upon said arch-like member.

16. The resilient automobile buffer comprising two substantially similar spring-

strip end-loop attaching elements, each having duplex attaching portions adapted to be secured to an automobile frame member and having a connector portion and end loop adapted to form a resilient end of the buffer front and having an inwardly extending connector portion coöperating with the adjacent connector portion of the element, and a front connector coöperating with the connector portions of said elements and clamping connector devices to connect the said front connector with the connector portions of said elements.

17. The resilient automobile buffer comprising two substantially similar spring-strip end-loop attaching elements, each having duplex attaching portions adapted to be secured to an automobile frame member and having a connector portion and end loop adapted to form a resilient end of the buffer front, and a front connector coöperating with the connector portions of said elements and clamping connector devices to connect the said front connector with the connector portions of said elements.

18. The resilient automobile buffer comprising two substantially similar resilient strip end-loop attaching elements, each having duplex attaching portions adapted to be secured to an automobile frame member and having a connector portion, adjacent impact receiving portion and end loop adapted to form a resilient buffer end and having an inwardly extending connector portion coöperating with the adjacent connector portion of the element, and a front connector coöperating with and substantially alining the connector portions of said elements and clamping connector devices to connect the said front connector with the connector portions of said elements.

19. The resilient automobile buffer comprising two resilient strip end-loop attaching elements, each having attaching portions adapted to be secured to an automobile frame member and having a connector portion, adjacent impact receiving portion and end-loop adapted to form a resilient buffer end and having an inwardly extending connector portion coöperating with the adjacent connector portion of the element, and a front connector coöperating with the connector portions of said elements and connector devices to connect said front connector with the connector portions of said elements.

20. The resilient automobile buffer comprising two resilient strip end-loop attaching elements, each having attaching portions adapted to be secured to an automobile frame member and having a connector portion and end-loop adapted to form a resilient buffer end, and a front connector coöperating with the connector portions of said elements and connector devices to connect

the said front connector with the connector portions of said elements.

21. A bumper for motor vehicles comprising a horizontally disposed member arranged transversely of the vehicle, arms connecting said member to the vehicle chassis, the outer portion of said arms curved outwardly away from each other, and a supplementary transverse and horizontal member supporting the forward portion of said structure, and means independent of the arms of the latter for connecting said supplemental member to the vehicle.

22. A bumper for motor vehicles, comprising a horizontally disposed member, the end portions whereof are bent inwardly and rearwardly to provide chassis supported arms, a supplementary member connected to the before-mentioned structure, and means independent of the arms of said first-mentioned member for securing said supplementary member to the vehicle.

23. A bumper for motor vehicles comprising a shock-receiving piece, supporting arms extended therefrom to the vehicle, a supplementary flexible member, means connecting the ends of said supplementary member to the before-mentioned structure, and devices independent of the supporting arms of the shock-receiving piece for connecting the supplementary member to the vehicle.

24. A bumper for motor vehicles comprising a horizontally disposed member, the end portions whereof are bent inwardly and rearwardly to provide arms for securing said member to the vehicle, a supplementary member connected to the before-mentioned structure, and means independent of the arms of the first-mentioned member for securing said supplementary member centrally of the vehicle.

25. A bumper for motor vehicles comprising a horizontally disposed member, the end portions whereof are bent inwardly and rearwardly to provide substantially parallel supporting arms, means for securing the ends of said arms to the vehicle, a supplementary member oppositely disposed with respect to said first-mentioned member, and connected thereto, and means independent of the arms of said first-mentioned member for securing said supplementary member centrally of the vehicle.

26. In a bumper for motor vehicles, a shock-receiving piece, members extended rearwardly therefrom and secured to the vehicle, in combination with a supplementary supporting structure consisting of a horizontally yieldable metal strap suitably connected to the aforesaid structure, and means, independent of said shock-receiving piece and its rearwardly extending members aforesaid, for connecting said supplementary supporting structure to the vehicle.

27. In a bumper for motor vehicles, a

shock-receiving piece, members extended rearwardly therefrom and secured to the vehicle, in combination with a supplementary supporting and shock-receiving structure connected to said first-mentioned shock-receiving piece, and means independent of the first-mentioned shock-receiving piece and its rearwardly extending members, for connecting said supplementary supporting structure to the vehicle.

28. A bumper for motor vehicles comprising a piece of strap metal bent to provide a shock-receiving piece, arms extended rearwardly from said shock-receiving piece and secured to the vehicle, and a secondary piece of strap metal connected to the first-mentioned piece and supporting the same from the chassis.

29. In a bumper for automobiles, an impact-receiving structure extending transversely of the vehicle beyond the opposite chassis side bars, spring supporting arms extending from the opposite end regions of said impact structure toward the chassis for support, said supporting arms having portions bowed with their convex portions faced toward the impact-receiving structure, in combination with a supplementary spring support for said impact structure, said supplementary support having a materially less transverse extent and being arranged between the impact structure and the chassis, said supplementary support comprising spring arms extending toward the chassis for support and extending from the mid-area of the impact-receiving structure in opposite directions on spring curves with convex portions faced toward the impact structure.

30. In a bumper for automobiles, an impact-receiving structure extending transversely of the vehicle beyond the opposite chassis side bars, spring supporting arms extending from the opposite end regions of said impact structure toward the chassis for support, said supporting arms having portions bowed with their convex portions faced toward the impact-receiving structure, in combination with a supplementary spring support for said impact structure, said supplementary support having a materially less transverse extent and being arranged between the impact structure and the chassis, said supplementary support comprising spring arms extending toward the chassis for support and extending from the mid-area of the impact-receiving structure in opposite directions on spring curves with convex portions faced toward the impact structure, together with means for uniting the impact structure and supplementary spring support.

31. A vehicle bumper comprising an impact structure extending transversely across the vehicle end, spring supporting arms extending from opposite end portions of the impact structure toward each other and to-

- ward the vehicle for support, in combination with a supplementary supporting structure for said impact structure, said supporting structure comprising spring arms extending 5 in opposite directions on spring curves from the mid-area of the impact structure and away from the latter, but toward the end-supporting arms therefor and toward the vehicle for support.
- 10 32. A vehicle bumper comprising an impact structure extending transversely across the vehicle end, spring supporting arms extending from opposite end portions of the impact structure toward each other and toward the vehicle for support, in combination 15 with a supplementary supporting structure for said impact structure, said supporting structure comprising spring arms adjustably connected to and extending in opposite directions on spring curves from the mid-area of the impact structure and away from the latter, but toward the end-supporting arms therefor and toward the vehicle for support.
33. A vehicle bumper comprising an impact member, spring arms for supporting opposite ends thereof, and a secondary sup-
- port for said impact member comprising spring arms affording an arch-like support self-sustained from the chassis.
34. A vehicle bumper comprising an impact structure, spring strip end supporting arms therefor, and secondary spring strip supporting arms of different thickness of metal.
- 35 35. A vehicle bumper comprising an impact structure, spring and supporting arms therefor, spring mid-supporting arms therefor, means common to the end and mid-supporting arms at opposite sides of the bumper respectively for securing the same to the vehicle and associated means for vertically adjusting the impact structure of the bumper.
36. A vehicle bumper comprising an impact member, coöperating pairs of end and mid-supporting arms therefor, and means for 45 supporting each of said pairs respectively at the outer sides of the opposite side bars of the chassis.

In testimony whereof I have signed my name to this specification.

RICHARD T. NEWTON.
